UNITED STATES PATENT OFFICE.

ZACKARIAH F. NANCE, OF EUFAULA, ALABAMA, ASSIGNOR OF ONE-HALF
TO ROBERT F. NANCE, OF SAME PLACE.

COTTON-PRESS.

SPECIFICATION forming part of Letters Patent No. 244,283, dated July 12, 1881.

Application filed May 2, 1881. (No model.)

To all whom it may concern:

Be it known that I, ZACKARIAH F. NANCE, a citizen of the United States, residing at Eu-
faula, in the county of Barbour and State of
Alabama, have invented certain new and useful
Improvements in Cotton-Presses; and I do
hereby declare the following to be a full, clear,
and exact description of the invention, such
as will enable others skilled in the art to which
it appertains to make and use the same, refer-
ence being had to the accompanying drawings,
and to letters or figures of reference marked
thereon, which form a part of this specification.

15 The present invention relates to that class
of cotton-presses in which a vertically-mova-
ble follower is operated by means of a vertical
screw and a revolving nut.

The invention consists in the combination,
20 with the follower and its screw, of a self-ad-
justing nut, which is composed of an external
shell having a concave end bearing, and in-
closing a nut proper having a convex end head.
The external shell is attached to the customary
25 levers or sweeps for operating the same, and
also has internal grooves which receive ribs
on the nut encircling the follower-screw.

In the drawings, Figure 1 is a vertical sec-
tional view of a screw cotton-press embody-
30 ing my improvements. Fig. 2 is a side eleva-
tion, showing the interlocking bars for secur-
ing the doors of the press-box. Figs. 3, 4,
and 5 are detail views of the revolving nut.

The letter A designates the casing and frame
35 of the press, having doors B at its upper end,
which constitute the walls of the bale-cham-
ber. These doors are hinged in the customary
manner, and are held in a closed position dur-
ing the performance of the baling operation
40 by means of a frame, C, surrounding the casing
of the press. This frame C consists of four bars
having gains or notches a cut in their ends for
interlocking the same, and rest upon pins or
projections b of the press-frame.

45 The customary platen, D, rests upon the top
of the doors or movable walls of the bale-
chamber, and is retained in position by means
of movable cleats E.

A head-block or cross-beam, F, at the base

of the press-frame receives a cylindrical tenon 50
or extension, G, of a shell, H, which incloses
the nut I. The latter fits loosely in the cylin-
drical socket of the shell H, and a concave
seat or cavity at the base of said socket re-
ceives the convex end or base of the nut I. 55
The shell H is provided with vertical grooves
h, and the nut I is constructed with ribs or
wings i, which enter said grooves and prevent
the nut from turning independently of its sur-
rounding shell. The nut I is preferably com-
posed of two parts of Babbitt metal and one
part of lead, and is molded on the screw J of
the follower K. By casting the nut on the
screw and turning it thereon the internal thread
is properly formed, owing to the ductile nature 60
of the metal employed. The shell H has its
seat in the top of the cross-beam F, and it rests
upon anti-friction balls or rollers f, placed in
the seat of the shell H. The projecting por-
tion or tenon G of said shell passes through 65
the beam F, and serves for the attachment of
the customary lever-arms or sweeps, L, em-
ployed for working the follower.

The shell H and interior nut, I, may be said
to constitute a follower-operating nut made of
two parts or sections, the interior portion or
nut proper having a movement independent
of its surrounding shell, to enable it to adjust
itself to the position of the screw. In this
manner the nut will not bind upon the screw 75
and become inoperative in case the outer shell
should be thrown out of a true horizontal plane,
or "out of plumb" in respect to the screw-sup-
porting beam F. By constructing the nut of
two parts in the manner stated all undue fric- 80
tion is avoided, and the press-follower can be
operated with greater ease and dispatch than
with any other form of operating-nut hereto-
fore devised. The wear of the nut is also ma-
terially lessened by permitting it to move in- 85
dependently of the surrounding shell, as has
already been stated. Said shell or external
portion of nut is generally constructed of cast-
iron, and it rests upon the anti-friction balls
or rollers, whereby it is made to turn easily. 90

I have in the present instance illustrated
a press box or frame which swings in a build-
ing between two joists, the follower moving

in an upward direction to compress the cotton in a top bale-chamber. It will be obvious, however, that the follower can move in a downward direction and compress the cotton in a bottom chamber, and that the press box or frame need not be movable, but can remain stationary.

Having thus described my invention, what I claim as new, and desire to secure by Letters

10 Patent, is—

1. In a cotton-press, the combination of the revolving nut constructed of an outer shell or section, H, having a concave bottom seat, and an inner nut or section, I, having a convex lower end and turning with the outer shell, with the press-box, follower-screw, and sweep or driving arms secured to the revolving nut, as and for the purpose set forth.

2. The outer shell or section, H, having a cylindrical extension or tenon, G, and socket provided with vertical grooves *h*, and concave end cavity or seat, and the interior nut or section, I, having wings or ribs *i* and a convex end, in combination with the press-box, follower-screw, and driving sweep or arms attached to the nut, as and for the purpose set forth.

20 In testimony whereof I affix my signature in presence of two witnesses.

ZACKARIAH F. NANCE.
